UNITED STATES PATENT OFFICE.

CHARLES T. E. GOULD, OF CHICAGO, ILLINOIS.

BATHTUB.

Application filed June 25, 1919, Serial No. 306,759. Renewed May 11, 1922. Serial No. 580,248.

To all whom it may concern:

Be it known that I, CHARLES T. E. GOULD, of the city of Chicago, in the county of Cook, State of Illinois, have invented new and useful Improvements in Bathtubs, of which the following is a specification.

This invention relates to stationary bath tubs such as are connected with a source of water supply, and my object is to devise means whereby the water supply is led to the bath at a plurality of points along its length. With such an arrangement it is possible to obtain a spray or sheet of water to wash off the sides and bottom of the bath, or, if desired, a needle bath effect may be obtained.

I attain my object by means of the constructions hereinafter described and illustrated in the accompanying drawings in which

20 Fig. 1 is a plan view, partly broken away, of a bath tub provided with my improvements;

Fig. 2 a cross section of the same looking towards the water connection end;

25 Fig. 3 a horizontal cross section showing a preferred arrangement of the water connections;

Fig. 4 an enlarged cross section through the rim of the tub showing the preferred arrangement;

Figs. 5, 6 and 7 are cross sectional details showing various modifications of the construction of the water channel of the tub;

30 Fig. 8 a sectional detail of the water controlling cock.

In the drawings like numerals of reference indicate corresponding parts in the different figures.

40 1 is a bath tub, which in the main is of ordinary construction, and is provided with the hot and cold water connections 2 and 3. In the preferred arrangement a pipe 4 forming a water channel extends along each side

45 of the bath tub. Preferably the pipe extends round the end of the bath tub remote from the water connections, so that the water channels at the opposite sides of the bath tub are connected. This pipe is preferably

50 located at the upper edge of the walls of the bath tub as shown in Figs. 2, 4 and 5. The pipe may be suspended by clips 5 as shown in Fig. 5 from the rim of the bath tub, but I prefer to support the pipe on a slight ledge 55 6 formed round the upper edge of the walls of the bath tub. This ledge supports the

pipe in such a way that perforations may be formed in the under side of the pipe which will direct jets of water down the sides of the bath. Certain of the jets may be directed diagonally inwards to give a needle bath effect if desired, or all the jets formed by the perforations in the pipe may be so directed if it is not desired particularly to use my arrangement for cleansing or rinsing the sides of the bath tub after the latter has been used.

In case the arrangement of the pipe forming the water channel is as shown in Fig. 2, it is preferable to omit the ordinary outwardly curled rim of the bath tub and employ instead a separate concavo-convex rim 7. The walls of the bath tub terminate without the usual rim, and the rim 7 sets on the edges as shown. If desired, for extra security, screws 8 may be employed to secure the rim to the walls of the bath tub. This rim gives the preferable rounded finish to the walls of the bath tub and completely conceals the pipe 4, while sufficient space is left between the inner edge of the cap and the inside of the wall of the bath tub to permit of the proper action of the jets of the pipe 4.

A further modification of the arrangement of the water channel is shown in Fig. 6. In this case the bath tub is formed with a hollow wall 9 from which jet openings 10 extend to discharge inwardly and downwardly into the bath tub.

70 A different arrangement is shown in Fig. 7, a water channel 11 being formed of a U-shaped pipe welded or otherwise secured to the outside of the wall of the bath tub, jet openings 12 extending through the wall of the bath tub into the water channel 11. Various other modifications may be devised which would fall within the scope of my invention.

The exact arrangement of the connections for the water supply to the pipe 4 or its equivalent are not material, though it is preferable to arrange them with as few taps as possible and so that the bath tub can be filled in the ordinary way if desired. In each case, it is essential that either hot or cold water or both mixed can be discharged in the usual way or through the pipe 4.

Referring particularly to Figs. 1, 2, 3 and 8, I show the preferred arrangement of the water connections between the pipe 4 and the ordinary water connections 2 and 3 of the

bath tub. The hot and cold water pipes 2 and 3 communicate with the usual fitting 13 with a common channel 14, which channel is controlled by the cock 15 which has a transverse waterway 16 formed therein, and a waterway 17 extending from the transverse waterway through one side of the cock plug. In the casing of the cock 15 is the hot water port 18, the cold water port 19, the discharge port 20 to the nozzle 21, and the discharge port 22 to the connection 23 leading to the pipe 4. When the handle 24 of the cock is turned straight down, both hot and cold water flow to the nozzle 21. When the cock handle is turned up, both hot and cold water will flow to the pipe 4. It will be noted that the ports 18, 19, 20 and 21 are wider than the transverse waterway 16 through the plug so that if the cock handle be turned up and slightly to the right, cold water alone will flow to the pipe 4. If it be turned up and slightly to the left, hot water alone will flow to the pipe 4 and by turning the cock handle a little way to one side or the other of the directly down position, either hot or cold water alone may be discharged to the nozzle 21.

The bath tub constructed as I have described has numerous advantages. The

water may be introduced simultaneously at 30 a number of points along the whole length of the bath tub, so that under any conditions the temperature of the water at each end of the bath tub will be the same. A spray of water down the sides of the bath tub is 35 easily obtainable to rinse the same and the effect of a needle bath readily obtainable by the use of diagonally directed jet openings in the pipe 4 or the equivalent water channels hereinbefore described. 40

What I claim as my invention is:—

A bath tub having a water channel extending along each side provided with downwardly directed openings within the tub; hot and cold water connections communicating with a common channel and provided with a nozzle leading from one side of the channel; a connection with the perforated water channel of the tub opposite the nozzle; and a single cock located at the junction of the nozzle and the connection with the perforated channel with the common channel of the hot and cold water connections controlling the flow of hot or cold water or both to the nozzle or to the aforesaid channel. 50 55

Signed at Toronto, Canada, this 6th day of June, 1919.

CHARLES T. E. GOULD.
